DESIGN FOR WOVEN FABRIC

William Teres, New York, N. Y.

Application February 2, 1937, Serial No. 67,401

Term of patent 3½ years

To all whom it may concern:

Be it known that I, William Teres, a citizen of the United States, residing in the city of New York, county of the Bronx, and State of New York, have invented a new, original, and ornamental Design for Woven Fabric, of which the following is a specification, reference being had to the accompanying drawing, forming part thereof.

The figure is a plan view of a section of woven fabric showing my new design.

The design comprises a background consisting of wavy moire lines extending in a generally lon-

gitudinal direction with respect to the fabric; this background being separated, at transversely spaced intervals, by contiguous longitudinal stripes of contrasting colors or shades; within each background area are two parallel lines of dobby figures or spots arranged in parallel relation to the stripes, and also arranged in parallel lines transversely of the fabric, substantially as shown.

I claim:

The ornamental design for woven fabric substantially as shown and described.

WILLIAM TERES.
